UNITED STATES PATENT OFFICE.

GEORGE HARTRICK, OF OAK PARK, ILLINOIS.

DESIGN FOR A BUTTON OR PIN.

51,065.

Specification for Design.

Patented July 24, 1917.

Application filed May 7, 1917. Serial No. 167,142. Term of patent 3½ years.

To all whom it may concern:

Be it known that I, GEORGE HARTRICK, a subject of the King of Great Britain, and having heretofore formally renounced my allegiance thereto and officially signified my intention of becoming a citizen of the United States, residing in Oak Park, county of Cook, and State of Illinois, have invented a new, original, and ornamental Design for a Button or Pin, of which the following is a specification, reference being had to the accompanying drawing, forming a part thereof.

On the drawing,

Figure 1 is a perspective view of a button or pin illustrating my new design; and

Fig. 2 is a front view thereof rotated ninety degrees.

Copies of this patent may be obtained for five cents each, by addressing the "Commissioner of Patents, Washington, D. C."

The design shown on the drawing consists of a button of globular shape and adapted to be fixed by any attaching means to a coat, as for example the stick pin shown. The outer part of the button is ornamented with white stars upon a blue field and the remainder of the button is ornamented with alternated red and white stripes.

I claim:

The new, original and ornamental design for a button or pin as shown and described.

GEORGE HARTRICK.
